UNITED STATES PATENT OFFICE

CHARLES E. PEARSON AND ERVY I. DAVIS, OF ST. PAUL, MINNESOTA

FURNACE HEAT CIRCULATOR

Application filed April 17, 1930. Serial No. 445,064.

Our invention relates to heat circulating devices in general and more particularly to a device for increasing the heating capacity of a furnace and so designed and operated as to create a desired uniform heating of rooms. The device is particularly applicable to so called warm-air furnaces and the main object of the invention is to provide a simple, inexpensive and highly efficient device for the purpose stated.

In the accompanying drawings,—

Fig. 1 is a slightly perspective, rear elevation of a warm air furnace and our improved device in operative position. Fig. 2 is a sectional elevation in horizontal plane through the lower part of the furnace, about as on line 2—2 in Fig. 1.

Fig. 3 is an enlarged detail view of the lower, rear part of the furnace partly in section, and a left hand exterior view of our device, about as on line 3—3 in Fig. 1 and looking toward the right from said line.

Fig. 4 is an approximately central, sectional elevation, in enlarged scale, of the lower part of the furnace and through our device about as on a vertical plane at line 4—4 in Fig. 2.

Fig. 5 is a modification of Fig. 2 showing a centrifugal type of fan.

Referring to the drawings by reference numerals, 5 designates the usual upright cylindrical type furnace for hot-air heating, said furnace surrounded concentrically by the shell 6. 7 designates the usual ash pit and its outlet through shell 6 normally closed by door 8 (see Fig. 2).

9 are the cool-air return pipes, shown as communicating with extended lower parts 6A of shell 6. In present type of furnaces the cool air thus returning is drawn upwardly between shell 6 and furnace 5 being heated as it rises and circulates through flues connected as at 6P (Fig. 1) or other means, not shown, to the rooms of a house.

10 in Fig. 1 designates the furnace smoke flue. The natural circulation and heating of the moving air is common to practically all warm-air furnaces, but various means have been devised to accelerate the warm air. Our device provides a simple and effective means

for this purpose as will now be described. The device is of such construction as to require no added flues or changes in the furnace. In the use of our device a quadrangular opening is made in the shell 6 at or near the floor. In this opening is fitted the large open end of a shell or sheet metal housing 12 of our device, said shell having parallel side walls 12A extending outwardly from the furnace and said side walls connected by a continuous sheet 12B, said parts at the outer end of the shell being rounded in the form of a half-drum. Concentric of said latter part is journaled a fan shaft 13 in the side walls, the shaft being extended exteriorly from one wall and carrying a driven belt pulley 14. 15 is an electric-motor having a drive pulley 16 on its spindle 16S alined with pulley 14 and connected therewith by a belt 17. 18 is a multi-blade propeller of paddle-wheel type, fixed on shaft 13.

19 is a partition member extending from the fan toward the end of housing 12 opening into the shell 6, said partition fixed to the side walls 12A and dividing the said mouth part of the shell 12 into an upper and a lower air passage, designated A and B respectively. When the fan is set in motion in proper direction, its action causes all the air at the base of the furnace to be drawn through passage B and be delivered with predetermined velocity through passage A, the latter current of air being directed upwardly and around the furnace, within shell 6. The upward direction of this air is facilitated by the inwardly and upwardly inclined fins or extensions 12C and 19C of members 12 and 19 respectively (see Fig. 4).

Obviously the air returning to the furnace in ducts 9 is drawn into the fan housing at the lower level as indicated by the arrows 20 and the means just described cause a forced upward circulation designated by arrows 21, the latter currents of air being heated by the furnace and being kept in forced circulation continuously by the fan.

The proportions of drive pulley 16 and driven pulley 14 must be governed by the motor speed and the required R. P. M.'s of the fan for proper forced circulation. Obvi-

ously the belt 17 is only shown as one form of drive, other means such as gear drive being perhaps desired in some cases. We have shown the motor mounted on a block 22 which is fixed to the floor 11.

In Figs. 1 and 2, 23 are upright, short supports of sheet iron or other suitable material, forming guards inwardly of the lower outlet of ducts 9, and both within the housings 6A, to prevent air from circulating directly upward after being discharged from said ducts. Thus such air is directed toward the fan housing.

In Fig. 5 a centrifugal type of fan 18 is shown and occupies approximately one half of the space in the housing. With this type of fan the cool air is drawn through passage B as before, then sucked into the central part of the fan as indicated by arrows 20A and blown out through passage A' (as arrows 21A). This passage A' is formed between a vertical partition 19P and a wall 12A to lead air directly toward the furnace but off center of the furnace so that the air current is started upwardly and around the furnace in a spiral action indicated by the arrows 21A.

The positive mechanical forced circulation of the air in the heating system provides for rapid circulation and an even temperature in all rooms heated by a furnace with means herein described, it having been found that in any part of a room whether at high or low levels the variation in temperature is negligible.

We claim:

1. In a warm air circulating device for furnaces having a central heating drum, a shell surrounding said drum concentrically, hot air outlet means in the upper part of said furnace, return-air intake means comprising pipes communicating with the lower interior of said shell, said circulating device comprising a fan housing mounted exteriorly of and fixed to the lower part of said shell and communicating with the interior thereof through an aperture provided therein, a radial winged fan mounted in the outermost part of said housing on a horizontal shaft journaled therein, said fan arranged to be rotated in a direction to draw air thru its housing from the lower part of said shell and to expel air from said housing into the space between the heated drum and said shell at an elevation above the said air intake action of the fan; a horizontal partition fixed in said fan housing between the fan and the furnace shell comprising a plate dividing that part of the fan housing into a lower and an upper air duct, inwardly and upwardly directed plate extensions of said upper duct formed integral thereof and located within the furnace shell for the purpose described.

2. An air circulating device for hot-air furnaces having an outer shell and an inner heating drum concentric thereof for generat-

ing warm air between it and the said shell, air return pipes connected with the lower interior part of the shell, warm air outlet means in the upper part of said shell for suitable heat distribution means; said circulating device comprising a horizontally elongated housing with one end fixed to said shell and opening thereinto at its lower part, said housing extending outwardly from the shell, a blower fan rotatably mounted in the outer end part of said housing, a horizontal partition within the housing in a common plane with the shaft of the fan and dividing the housing into an upper and a lower duct between said fan and the shell, said fan adapted to be rotated in a direction to draw air toward it through the lower duct from the lower part of the shell and to forcibly expel said air through said upper duct into the shell and around said heating drum in an upward direction from the outlet end of said upper duct, means for directing said latter air current in an upward direction comprising upwardly inclined extension plates between said shell and heating drum and comprising integral parts of said upper duct.

3. In a warm air circulating device for furnaces having a central heating drum, a shell surrounding said drum concentrically, hot air outlet means in the upper part of said furnace, return-air intake means comprising pipes communicating with the lower interior of said shell; said circulating device comprising a fan housing mounted exteriorly of and fixed to the lower part of said shell and communicating with the interior thereof through an aperture provided therein, a radially winged fan mounted in the outermost part of said housing on a horizontal shaft journaled therein, and a horizontal partition in said fan housing between the fan and the aperture of said housing, comprising plate means dividing said part of the fan housing into a lower air intake passage and an upper air outlet passage.

In testimony whereof we affix our signatures.

CHARLES E. PEARSON.
ERVY I. DAVIS.
